UNITED STATES PATENT OFFICE.

SAMUEL J. TURNER, OF CHICAGO, ILLINOIS; ASSIGNOR, OF ONE-HALF TO OTTO RABE,
OF WILMETTE, ILLINOIS.

STRAP-TIGHTENER.

1,319,126.

Specification of Letters Patent.

Patented Oct. 21, 1919.

Application filed March 7, 1919. Serial No. 281,126.

To all whom it may concern:

Be it known that I, SAMUEL J. TURNER, a citizen of the United States, residing at Chicago, in the county of Cook and State of Illinois, have invented certain new and useful Improvements in Strap-Tighteners, of which the following is a specification.

In the application of metal bands or straps to boxes, cartons, bales, etc., for holding such bodies firmly together, it is necessary to adequately tighten such metal ribbons or tapes and various styles of appliances have heretofore been proposed to accomplish this work, but, so far as I am advised, all of these mechanisms have one or more serious faults when considered from a structural, manufacturing, or operative standpoint.

The leading object of this invention is to provide an apparatus of this general character which will overcome these previously existing defects, which is simple in structure, which is inexpensive to produce, which with small manual effort produces the desired constricting or shortening of the band or strap, and which is unlikely to become damaged or injured in service.

In order that those skilled in this art may have a full and complete understanding of the invention and its various advantages I have illustrated in the accompanying drawing, forming a part of this specification and throughout the various views of which like reference characters refer to the same parts, a preferred and desirable embodiment of the invention, but it is to be understood that the invention is not limited and restricted to this particular embodiment since the invention is susceptible of a variety of embodiments all incorporating its main or principal features and elements.

In this drawing:

Figure 1 is an elevation of the apparatus showing the manner in which it grips the two ends of the band or strap to be tightened;

Fig. 2 is a plan view of the structure, the operating handle being shown in section;

Fig. 3 is a cross-section on line 3—3 of Fig. 2.

Referring to the drawing it will be observed that the appliance comprises two end supporting bodies or parts 10 and 11 connected together by a pair of parallel, cylindrical rods 12, 12 the ends of which are fitted

and fixedly secured in cavities or recesses in such terminal elements. On its top each of such end bodies is cut away or reduced in thickness at 13 and in such two aligned or registering spaces the end portions of a ratchet-bar 14 are fastened as by countersunk screws 15, 15, such bar having its ratchet-teeth on and disposed transversely of its top surface. Thus the parts 10, 11, 12 and 14 unitedly or conjointly form a stiff, rigid, strong frame for supporting and coacting with the other parts of the device. A flat bar 16 is fastened crosswise the appliance to the under portion of the end body 11, being received in a transverse groove in its bottom face provided for that purpose, and such bar or plate extends laterally or transversely of the appliance beyond the lower part of the body forming a shelf or ledge for receiving the band or strap to be tightened. Above such protruding or projecting part of the bar, the body 11 is fitted with an eccentric or cam clamp 17, provided with a handle 18, adapted to grasp and securely hold the band or strap between itself and the bar all as will be readily understood. This eccentric clamp is fulcrumed on a shaft 19, suitably fixed in the main portion of the part 11 and in a right-angle extension or arm 20 integral with and extended forwardly from the main body.

A block 21, recessed on its top for the accommodation of the ratchet-bar 14, is apertured to receive the guide rods 12, 12 on which it is supported and slidable lengthwise the device. Such block is also equipped with a transverse bar or plate 21 and an associated eccentric or cam clamp 22 fitted with an operating-handle 23. As is clearly shown, these two clamps of the end body and the reciprocating block are in register and at one side of the main portion of the appliance to readily receive the terminal portions of the band or strap 100 to be tightened or made tense, whereby such band ends may be clamped or fastened together by means of a clip 101 adapted to be interlocked to the overlapped ends of the strap by an apparatus not shown enabling the band to perform its constraining, constricting and confining function.

In ears 24, 24 upstanding from the reciprocating block on a non-rotating shaft 25, a gear sector 26, supplied with a rock-handle 27, is fulcrumed or hinged, the teeth thereof

being in mesh or interfitting engagement with those of a sliding rack-bar 28 positioned over the ratchet-bar and longitudinally grooved at 29 on its under face to escape conflict with the teeth of the ratchet-bar. This rack-bar rests and slides on those smooth side portions 30, 30 of the ratchet-bar, not provided with teeth, being prevented from crosswise or lateral displacement by the ratchet-teeth and the ears 24, 24.

To prevent movement of the rack-bar away from the band clamp 16, 17 and at the same time permit its approach toward such clamp, the bar is supplied with a pawl 31 pivoted thereto by means of a hinge or pivot pin 32 and spaced projections 33, 33 supporting it, the pawl overlying and coöperating with the stationary ratchet-teeth in the usual manner. In a similar way and for a similar purpose block 21 is supplied with a pawl or dog 34 hinged to the block at 35 and straddling and coacting with the teeth or beveled projections of the ratchet-bar.

25 The operation of the apparatus is as follows: One end portion of the flat metal band or strap 100 which encircles the body to be bound or confined is inserted between the plate 16 and clamp 17 whereupon the latter is turned by its handle 18 to grip or grasp the metal band or ribbon securely and firmly. If desired, the top surface of such bar or plate may be knurled or roughened to insure the efficiency of this holding action.

30 In like manner the other end of the metal strap or tape is clamped between the gripping members 21 and 22 of the reciprocatory block, which, by releasing or lifting the pawls, may be shifted or slid away from the 40 clamping elements first mentioned. Both pawls or dogs now engaging the teeth of the rack-bar, the handle 27 is swung to the left which slides the rack-bar and its pawl to the right, the latter easily riding over the 45 beveled or sloping teeth of the stationary ratchet-bar. During this action block 21 and its pawl remain stationary. Then handle 27 is rocked to the right, and, inasmuch as the rack-bar is held against sliding to the 50 left by its pawl coöperating with one of the rack teeth, block 21 is forcibly shifted to the right, tightening the band clamped to it, its pawl readily traveling over the ratchet-bar teeth. While the slideable block with 55 the strap or band clamped thereto is prevented from retrograde travel to the left by its pawl, handle 27 is swung to the left again advancing the rack-bar to the right another step, and then rocked to the right 60 again carrying the block still farther in the same direction thus additionally tightening and stretching the band. This alternate rocking action of the handle is continued until the strap or band ends overlap, which 65 overlying parts are fitted with a fastening

clip 101 intended to be deformed or bent by a separate tool, not shown, and unnecessary here to describe. After this piece of work is completed, the fastened band is released from the device by freeing the two eccentric 70 clamps, the appliance as a whole then being moved sidewise away and free from the band.

The attainment of the specified objects and purposes in the device presented will 75 be readily appreciated by those skilled in the art who will understand that various minor mechanical changes may be incorporated in the structure presented without departure from the heart and essence of the 80 invention and without the sacrifice of any of its substantial benefits and advantages.

I claim:

1. In a strap-tightener of the character designated, the combination of a support, 85 a ratchet-bar thereon, a block slideable on said support, means to clamp a section of the strap to be tightened to said support, means to clamp a section of such strap to said block, a rack slideable on said support, a gear-sector fulcrumed on said slideable block and in mesh with said rack, a handle to rock said sector, a pawl on said rack adapted to coact with said ratchet-bar, and a pawl on said slideable block coöperating with said 95 ratchet-bar, whereby oscillation of said gear-sector by its handle intermittently advances said block and its strap-clamp toward the companion strap-clamp, substantially as described. 100

2. In a strap-tightener of the character designated, the combination of a support, a strap-clamp thereon, a block slideable on said support toward and from said clamp, a companion strap-clamp on said slideable 105 block, a gear-sector fulcrumed on said block, a handle to rock said gear-sector, a rack slidably mounted on said support and in mesh with said sector, adjustable means to prevent the rack from moving away from 110 but permitting its movement toward the clamp on said support, and adjustable means to prevent the block from moving away from but permitting its movement toward the clamp on the support, substantially as described. 115

3. In a strap-tightener of the character designated, the combination of a support, a strap-clamp thereon, a block slideable on said support toward and from said clamp, a companion strap-clamp on said slideable block, a gear-sector fulcrumed on said block, a handle to rock said gear-sector, a rack slidably mounted on said support and in mesh with said sector, automatically adjusting means 120 to prevent the rack from moving away from but permitting its movement toward such support clamp, and automatically adjusting means to prevent the block from moving away from but permitting its movement to- 125 130

ward said support clamp, substantially as described.

4. In a strap-tightener of the character described, the combination of a pair of end bodies, a pair of rods connecting said bodies together, a ratchet-bar connected to said bodies, a strap-clamp on one of said end bodies, a block slideable on said connecting- rods toward and from said clamp, a compon-

ion strap-clamp on said slideable block, a 10 gear-sector fulcrumed on said block, a handle to rock said gear-sector, a rack slideable on said ratchet-bar with its teeth in mesh with those of said sector, a pawl on said rack co-operating with said ratchet-bar, and a pawl 15 on said block co-operating with said ratchet- bar, substantially as described.

SAMUEL J. TURNER.
